Inventor:

James W. Trew,

By Geo. W. Ayer.

Attorney.

UNITED STATES PATENT OFFICE.

JAMES W. TREW, OF DUBUQUE, IOWA.

PLOW OR HARROW ATTACHMENT.

SPECIFICATION forming part of Letters Patent No. 389,121, dated September 4, 1883.

Application filed November 1, 1887. Serial No. 253,967. (No model.)

To all whom it may concern:

Be it known that I, JAMES WILLIAM TREW, a citizen of the United States, residing at Dubuque, in the county of Dubuque and State of Iowa, have invented certain new and useful Improvements in Plow or Harrow Attachments; and I do hereby declare the following to be a full, clear, and exact description of the invention, which will enable others skilled in the art to which it appertains to make and use the same.

This invention relates to a sulky attachment for plows, harrows, &c., by means of which a comfortable seat will be afforded the driver, and which can be made very easily and cheaply by any one of ordinary mechanical skill and ability; and, moreover, it can be instantly attached to or detached from the plow, harrow, &c., with which it is to be used.

By the use of my invention the expense necessitated by plowing or harrowing will be materially diminished by reason of the driver not being so easily fatigued, and further allowing the team to increase its speed, there being no back pull on the horses' heads, as is invariably the case when the driver walks beside them.

This invention relates, further, to a new and improved method of attaching the wheels to their axles, diminishing the expense, and increasing the strength, portability, durability, and general appearance of the device, as well as in other but less important details of construction, all of which will be more fully hereinafter described and claimed, and which are illustrated in the accompanying drawings, in which—

Figure 1 is a perspective view of the entire device. Fig. 2 is a sectional view of the axle, showing the manner of attaching the wheels thereto; and Fig. 3, a sectional view illustrating the manner of detachably attaching the device to the plow, harrow, or whatever implement it is to be used with.

Like letters have reference to identical parts in all of the above views.

A is the seat or saddle on which the driver sits, or, rather straddles, in the manner of one riding a bicycle. This seat is made preferably of wood and of the form illustrated, and is

provided in its extreme front end with a long annular chamber, into which the end of the curved iron rod *a* is inserted. Attached to the extreme rear portion of this seat or saddle 55 A is the axle B, made preferably of metal, though it will be apparent that this axle could be made of wood, provided the requisite strength could be obtained. This axle is provided in each end with a long annular chamber, *b*, and with an internally-screw-threaded opening, *c*, leading from the outside down into each chamber *b*. The bearing-pins *dd*, provided with cylindrical heads *e*, and on which the wheels C rotate, are inserted into these chambers *b b*, and are each provided with an internally-screw-threaded opening, *ff*, therein, extending down about half through the same, and which, when all are in proper position, will be in line with the screw-threaded openings *e e*, 70 which are of the same internal diameter. A set-screw, *g*, passed down through the openings *e* and *f* and driven tightly home, will now securely lock the bearing-pins *dd* in place. It will of course be understood that the wheels 75 should be in position on the bearing-pins before the set-screws *g g* are inserted. The iron rod *a* is locked inside of the chamber in the front portion of the seat or saddle in a similar manner by means of the set-screw *h*.

I have found by actual manufacture of my device and by practical working of the same that the rod *a* and axle B can be made easily and cheaply out of iron or steel piping, and will possess great strength and durability; and 85 I have found, further, from the same source, that old gas-pipe, which can be procured at but slight expense, answers the purpose extremely well.

In Fig. 3 is shown the manner of attaching 90 the device to the plow or harrow, &c.; and it consists, simply, of a pin, *i*, driven into any convenient portion of the wooden frame-work of the implement, and over which the hollow vertical portion of this rod *a* fits. It will be 95 evident that in the case of some harrows, in which the teeth extend entirely through the frame-work, the hollow end of the rod *a* can be inserted over any convenient one of these teeth. By either of these arrangements it will 100 be seen that the whole device will trail behind the implement to which it is attached, and

will always be in the center of the line of draft, the pin *i* acting as a pivot.

By the particular manner of fastening the wheels in place I dispense with the continually-loosening nuts on the end of the axle which have heretofore been employed, and which are a continual source of annoyance to the farmer, and use instead the integral cylindrical heads *e e* on the ends of the bearing-pins *d d*.

I do not wish to be limited to a plow or harrow attachment, as my device might be attached to the end of a wagon, so as to form an auxiliary seat; neither do I wish it under-
stood that my device can only be attached to a common farming-plow, as it could be used with good results with a snow-plow.

It is not absolutely necessary to make the saddle *A* precisely as I have described, as it could be fastened on the end of a leaf-spring, like the seats at present used on mowing-ma-

ches; but to accomplish this would require mechanical and not inventive skill.

Having thus described my invention, what I claim as new therein, and am desirous of protecting by Letters Patent, is—

In a riding attachment for plows or harrows, the body or seat having perforations for the wheel-spindles and for the attaching device, in combination with the wheel-spindles and their set-screws, and the curved tubular connecting-rod adjustable by a set-screw, whereby the frame is adapted for connection with a plow or harrow, substantially as and for the purpose set forth.

In testimony whereof I affix my signature in presence of two witnesses.

JAMES W. TREW.
